UNITED STATES PATENT OFFICE.

JOHN Z. DUDLEY, OF LINDALE, TEXAS, ASSIGNOR OF ONE-HALF TO CHARLES E. JOHNSTON, OF DALLAS, TEXAS.

HAY-PRESS.

1,242,158.

Specification of Letters Patent.

Patented Oct. 9, 1917.

Application filed December 16, 1915. Serial No. 67,093.

To all whom it may concern:

Be it known that I, JOHN Z. DUDLEY, a citizen of the United States, residing at Lindale, in the county of Smith and State 5 of Texas, have invented certain new and useful Improvements in Hay-Presses, of which the following is a specification.

My invention has relation to an improvement in baling presses and in such connection it relates more particularly to the arrangement and construction of the means for operating the plunger of the press whereby reciprocation of the plunger may be secured by the revolution of an arm or lever whereby a single or double reciprocation of the plunger during a single revolution of the arm or lever may be secured as desired.

The present form of baling press is especially adapted to be operated by horse power and in the carrying out of my invention, a crank shaft, arranged to reciprocate the plunger of the press, is turned by a long arm or lever, one end of the lever being secured to the crank shaft and the other end attached to the horse by rope or chain. It follows that the horse travels with the lever in a circle, the crank shaft is turned to reciprocate the plunger. A spring assists in withdrawing the plunger from the press.

The present invention resides more especially in the means whereby the arm or lever is connected with said shaft—said means being adjustable or convertible so 35 that for a single revolution of the arm or lever the crank shaft may be either continuously rotated to give a single in and out motion of the plunger or the arm may be released from the shaft during the continuous 40 rotary movement of the arm to permit the spring to return shaft and plunger to a position where a new stroke of the plunger takes place and the arm is thereafter locked to the shaft to thereby secure two movements 45 to the plunger during a single, continuous rotation of said arm.

The nature and scope of my invention will be more fully understood from the following description taken in connection with 50 the accompanying drawings, forming part hereof, in which,—

Figure 1, is a top or plan view of a baling press embodying the main features of my invention;

55 Fig. 2, is a side elevational view thereof;

Fig. 3, is a longitudinal sectional view of the same;

Fig. 4, is an end elevational view;

Fig. 5, is an enlarged horizontal sectional view taken on line 5—5 of Fig. 3;

Fig. 6, is a top or plan view partly broken away to show the connection between the arm or lever and the crank shaft; and

Fig. 7, is a vertical sectional view taken on line 7—7 of Fig. 6.

Referring to the drawings, 1 represents the packing box and 2 the plunger. The plunger 2 is connected by link 3 with the crank 4 of a vertically disposed crank shaft 5. This crank shaft 5 is suitably supported by a bearing 5^a in the base 6 of the press and a bearing 7 in the framework 8 extending above said base 6. Above the bearing 7, the shaft 5 is provided with a ratchet 9 secured to the shaft and traversed as at 10 by an aperture or opening for a purpose to be hereinafter described.

Suspended by frame 11 to swing on the shaft 5 is an arm or lever 12, the front or shaft end of the lever having two brackets 13 inclosing the ratchet 9 and traversed by said shaft 5. The brackets 13 form a pivotal support for a pawl 14, normally engaging the ratchet 9. A spring 15 fastened at one end to arm 12 or brackets 13 bears at its free end on the pawl 14 to hold said pawl in the teeth of ratchet 9.

A spiral spring 16 connects the plunger operating link 3 with the framework 8 and serves normally to pull said link 3 and plunger 2 outward from the box 1.

So far as described it is manifest that the lever or arm 12 when turned about the shaft 5 will, through said ratchet 9, turn the shaft approximately a half revolution or until the spring 16 is extended sufficiently to pull the plunger and link back to normal position.

The spring 16 thus draws back the crank 4 to initial position before said crank has passed its half revolution. This slipping backward or reversal of the shaft 5 is permitted through its ratchet 9 and pawl 14 connection with the arm or lever 12. In slipping backward the ratchet passes under the pawl 14 which however again engages 105 the teeth as the arm 12 revolves after the crank shaft has passed or turned backward to its normal position.

The operation continues, there being two back and forth strokes to the plunger 2 to 110

one complete revolution of the arm or lever 12.

If it is desired to have but one complete stroke to the plunger 2 for each revolution 5 of said arm 12, a bolt 17 is passed through the brackets 13 and the opening 10 traversing the ratchet 9. The arm or lever 12 is thus locked to the ratchet 9 and hence to shaft 5 and the spiral spring 16 cannot 10 therefore pull the shaft 5 backward since the shaft is positively locked to said arm or lever 12.

The power used ordinarily to operate the arm or lever 12 is horse power, the horse 15 stepping across platform 18 and over the link 3 as it travels in a circle.

Having thus described the nature and objects of my invention, what I claim as new and desire to secure by Letters Patent is,—

20. 1. In a baling press, a crank shaft, a link connected with said shaft, a plunger operated by the link, a spring arranged to move the link and crank shaft in one direction, a ratchet mechanism secured to said shaft, and 25 a lever arm and pawl, said lever arm arranged to swing on the shaft to operate through said pawl the ratchet mechanism

and thereby operate the shaft in one direction against tension of said spring, in combination with means for locking the ratchet 30 to said lever arm during the entire revolution of said arm.

2. In a baling press, a crank shaft, a frame, wherein said shaft is arranged to turn, a plunger, a link connecting the plunger to the crank of said crank shaft, a spring extending from the frame to the link and adapted to retract the plunger, a ratchet secured to the crank shaft, a sweep arm arranged to swing on said crank shaft, brackets carried by the sweep arm and arranged adjacent to the ratchet, a pawl pivotally supported by the brackets and engaging the ratchet and a bolt removably traversing the brackets and ratchet to lock the sweep arm 40 directly to said ratchet.

In testimony whereof I have signed my name to this specification in the presence of two subscribing witnesses.

JOHN Z. DUDLEY.
